(57) **CLAIM**

The ornamental design for a shoe, as shown and described.

DESCRIPTION

The sole FIGURE is a top, right, and front perspective view of an ornamental design for a shoe.

The dash-dash-dash broken lines are included for the purpose of illustrating portions of the shoe that form no part of the claimed design. The dash-dot-dash lines are included for the purpose of illustrating boundary lines and form no part of the claimed design. A transition in tonal contrast shown along the front cushion is claimed.
